C. H. WALKER,
COMMUTATOR,
APPLICATION FILED OCT. 30, 1919.

Patented Apr. 26, 1921.

FIG 1

FIG 2

Inventor
Clarence H. Walker
By his Attorney
H. H. Dyer

UNITED STATES PATENT OFFICE.

CLARENCE H. WALKER, OF LARCHMONT, NEW YORK.

COMMUTATOR.

1,375,945.

Specification of Letters Patent. Patented Apr. 26, 1921.

Application filed October 30, 1919. Serial No. 334,424.

To all whom it may concern:

Be it known that I, CLARENCE H. WALKER, a citizen of the United States, and a resident of Larchmont, county of Westchester, 5 and State of New York, have invented certain new and useful Improvements in Commutators, of which the following is a specification.

My invention relates to commutators, such 10 as timers, distributors and the like, for the ignition current of internal combustion motors.

For the purposes of affording an understanding of my invention I illustrate and 15 describe same herein in connection with its use as a timer for the Ford automobile engine.

The present engine is more especially concerned with the improvement of the shell 20 carrying the relatively stationary contact members, which shell is adjustable to advance or retard the spark in well known manner. A rotating element serves to carry the ignition current in succession to the 25 various members contained in such shell.

According to present invention, such shell member is made of refractory material, such as porcelain, and the openings to receive the contact members are formed there- 30 in and the contact members are separately secured in such openings in the completed shell, as by being bolted in place therein. The openings for the contact members are preferably formed in molding, or casting, 35 or otherwise forming the shell of refractory material.

My improved shell can be readily and cheaply constructed, and none of the difficulties are encountered which occur, for example, 40 with the insertion of metallic inserts in making shells of molded material, such as bakelite, condensite or the like. The shell of refractory material is its own insulator, and metallic inserts can be secured therein 45 directly and without the provision of any separate insulating members, such as are required, for example, when a metallic shell is made use of, requiring separate insulating pieces of fiber or the like materials.

With the foregoing and related objects in view, my invention consists in the features of construction and combinations herein set forth and claimed.

In the drawing forming a part of the 55 specification, Figure 1 is a top view of a

Ford timer shell, in accordance with my invention.

Fig. 2 is a sectional view taken substantially on the broken line 2—2, Fig. 1, and also showing in section the mounting of the 60 device in the Ford automobile engine. The shell 10 is of refractory, moldable, electrically insulating material, such, for example, as porcelain. When constructed of porcelain, which is a good embodiment of the 65 invention, the openings for the contact members are formed in molding the material. In the form shown such openings, which are indicated generally by the reference numeral 11, are provided with top 70 and bottom recesses 12 and 13, serving respectively, for the reception of the head 14 of the contact member 15 and the washer 16 of yielding material, such as fiber or the like, which is preferably placed under the 75 nut 17 in securing the contact member 15 in place in the commutator. The binding nut 18 may serve also the function of a lock nut for assisting in the holding function of nut 17. The two nut arrangement shown is 80 preferable for cheapness and simplicity, but the contact members may be fastened into the shell after the same has been completed, in various other ways. In the form shown there are four contact members 15, but the 85 number thereof corresponds to the number of engine cylinders served by the commutator, as will be understood. The operating lever 19 for the commutator is made integral with the shell 10 and is provided with 90 the customary opening 20 for the actuating device, such as a link or other connecting part, which serves to turn the shell 10 to advance or retard the spark.

The rotating member may be of various 95 forms. In the form shown the rotary shaft 21, which in the Ford automobile engine is the cam shaft, has a sleeve 22 fast thereon, and having a link 23 pivoted thereto. Contact point 25 is carried on link 23 and spring 100 24 acts to press said point against the interior race 26, which forms an integral part of shell 10, and point 25 makes contact, as it is rotated, with the heads 14 of the contact members 15, thereby insuring the proper 105 distribution of the electrical current for ignition purposes. The spring member 27 provided with the knob or point 28, entering the central recess or depression 29 in the top of the shell 10 serves to hold the same 110

in place on its seat and also serves, to some extent, as an outer bearing therefor, as in the customary Ford practice.

While it is the preferable construction to 5 form the openings 11 for the contact members 15 with their axes extending substantially parallel to the axis of rotation of the operating shaft, the same may be arranged in different relations, as for example, the 10 contact members may be placed in the lateral flange 30 of the shell 10, in which case, of course, the rotating member of the commutator will be constructed to coöperate therewith, as, for example, in the ordinary 15 manner now in common use in the timer of the Ford automobile engine.

Commutators in accordance with my invention have numerous advantageous features. The shell is simply and cheaply constructed; is sufficiently strong and durable for the purposes for which it is intended; difficulties of molding the shell with metallic contact members in place therein are avoided, and the shell itself acts as its own 25 insulating device.

The hardness and capacity of the porcelain to resist wear is substantially equivalent to the hardness and wear resisting capacity of steel, so that the shell, instead of 30 being grooved out by wear in use, and the contact surfaces projecting to form raised places or bumps, as in the case of shells

made of fiber, bakelite and other insulating materials, remains smooth and wears slowly and evenly and has an extremely long useful 35 life requiring practically no attention in use.

In my claim I refer to a shell of "ready molded" refractory material in order to define the fact that the shell is made complete 40 by molding before the contact pieces are secured in place therein.

It is to be understood that the form shown is intended only for illustrating my invention and affording an understanding thereof, and that modifications and changes may be resorted to within the scope of my claims, by which my invention is defined.

I claim:

An ignition commutator for internal combustion motors, comprising a contact member carrying shell of ready molded porcelain, and metallic contact members secured in place therein, the race for the rotating member of the commutator being of porcelain and integral with the material of the shell, whereby the shell serves as its own insulator and the race is substantially as wear resisting as the metallic contact members.

In testimony that I claim the foregoing, I hereto set my hand, this 29th day of October, 1919.

CLARENCE H. WALKER.
